UNITED STATES PATENT OFFICE.

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO.

DOOR.

Application filed June 27, 1924. Serial No. 722,761.

This invention relates to improvements in car doors.

One object of the invention is to provide a car door for box cars, wherein great strength 5 against pressure in each direction is obtained.

Another object of the invention is to provide a door of the outside sliding type, and more particularly for box cars, so constructed and braced as to provide maximum strength.

10 A still further object of the invention is to provide a car door constructed entirely of metal, composed of a plurality of panels, wherein the joints between the panels are effectively braced to provide maximum 15 strength.

Still another object of the invention is to provide a simple and efficient operating mechanism for car doors of the sliding outside type.

20 Other objects and advantages of the invention will more clearly appear from the description and claims hereinafter following.

In the drawings forming a part of this specification, Figure 1 is a side elevational view of a portion of a car showing my improvements in connection therewith, the parts being broken away in order to better accommodate the figure on the sheet. Figure 2 is an enlarged, broken, horizontal, sectional view 30 corresponding to the section line 2—2 of Figure 1. Figure 3 is an enlarged, vertical, sectional view corresponding to the section line 3—3 of Figure 1. Figure 4 is a still further enlarged vertical, sectional view of the joint 35 between two panels of the door. Figure 5 is an enlarged, horizontal, sectional view of the rear edge portion of the door. Figure 6 is a view similar to Figure 3 illustrating a different embodiment of the invention. Figure 40 7 is an enlarged, detailed, front, elevational view of a guide bracket used in connection with the construction illustrated in Figure 6. Figure 8 is a view, partly in plan and partly in horizontal section, of the bracket shown in Figure 7. And Figure 9 is an enlarged, vertical, sectional view of the upper end of the door illustrated in Figure 6, the section being taken through one of the guide brackets. 45 Referring first to the construction illustrated in Figures 1 to 5 inclusive, 10 indicates the usual side wall of a box car, 11 the floor boards, 12 the car side sill, 13—13 the door posts or jams at the front and rear ends of the door opening and 14 the lintel.

In the arrangement illustrated in Figures 55 1 to 5 inclusive, a sliding outside door is shown designated generally by reference character A. The door A is composed of metal throughout and comprises a plurality 60 of panels. In this instance, the door is shown as composed of an upper panel 15, a lower panel 16 and an intermediate panel 17. Each 65 of the panels is of rectangular outline and is dished inwardly, thereby providing each panel with a continuous flange 18 extending along the four edges thereof, and an inclined, continuous wall 19 connecting the flange to the main body portion of the panel. The sections of the flange 18 on the four sides of each 70 panel are all parallel to the main body portion of the same, but that portion of each flange of the panels 16 and 17 at the upper side thereof is inwardly offset with reference to the remainder of the flange a distance corresponding 75 to the thickness of the metal of the panel, so as to extend beneath the flange in the lower side of the adjacent panel. As clearly 80 shown in Figure 3, the sections of the flanges at the lower sides of the panels 15 and 17 over-lap the sections of the flanges at the upper sides of the panels 17 and 16, thereby presenting corrugations 20 extending horizontally. Each of the corrugations 20 is reinforced by a longitudinally extending strip 85 21 of trough shape, inserted within the same and closely fitting the inclined walls 19 and the inner face of the innermost of the overlapping flange sections 18. The over-lapping flange sections of the adjacent panels are secured to each other and united with the corresponding strip 21 in any suitable manner, the same being shown as riveted together. 90 Each of the corrugations 20 is also reinforced by a flat strip 22 spanning the corrugation and extending horizontally, the upper and lower 95 edges of the strip being riveted to the main body portions of the corresponding panels adjacent the base of the corrugation. In addition to stiffening and bracing the corrugations, the strips 22 serve as an additional means for securing the panels together, and also prevent any of the load from lodging in the corrugations 20. As clearly shown in Figures 3 and 4, the free edges of the side flanges of each channel strip 21 abut the corresponding strip 22, thereby giving the corrugation additional strength and rigidity. 100

A relatively heavy Z-bar 23 having the

flanges 24 and 25 thereof vertically disposed and extending upwardly and downwardly respectively from the intermediate section 26, extends longitudinally of the lower edge of the door and is secured thereto by the flange 24 which is riveted to the rear surface of the section of the flange 18 at the lower edge of the panel 16. A reinforcing bridging strip 27, extending lengthwise of the door and 10 spanning the space between the body portion of the panel 16 and the Z-bar 23, is secured at its upper and lower edges to the panel 16 and the flange 25 respectively. The lower edge of the strip 27 terminates flush with the lower 15 edge of the member 25, thereby providing a depending flange of two-ply thickness at the lower edge of the door, engaging behind an angle bar track 28 supported by brackets 29 fixed to the side sill 12 of the car. The 20 depending flange at the lower end of the door is offset slightly inwardly from the plane of the body portion of the door panels and is guided between the side wall of the car and the track as clearly shown in Figure 3, and 25 extends an appreciable distance below the track to prevent accidental disengagement of the same from its guideway, the brackets 29 being each provided with an upwardly extending arm on which the track is supported 30 to thereby accommodate the depending guide flange.

A relatively heavy channel bar 30, having short and long flanges 31 and 32, extends vertically along the rear edge of the door, the 35 same being secured to the flange sections 18 at the rear ends of the panels 15, 16 and 17 by means of the flange 32, by rivets, or secured in any other suitable manner. A vertically extending bridging strip 33, having one edge 40 angularly disposed as indicated at 34 and riveted to the inner surface of the intermediate section of the channel bar 30, spans the space between the channel and the main body portion of the panels 15, 16 and 17, being 45 rigidly secured to the latter in any suitable manner, as by spot welding. The flange 31 of the channel bar 30 extends inwardly of and is spaced an appreciable distance from the rear side of the door, being adapted to engage 50 over a rearwardly projecting arm of an angle bar 34' riveted to a wear face plate 35 applied to the exposed face of the post 13 at the rear end of the door opening. The over-lapping portions of the angle bar 34' and the channel 55 bar 30 form an effective spark and weather seal. A relatively heavy Z-bar 36 extends vertically of the front edge of the door and has one flange thereof secured to the flange sections 18 at the front ends of the panels 15, 60 16 and 17 and has the other flange thereof projecting forwardly from the door and riveted to a vertically disposed reinforcing bridging strip 37 spanning the space between the Z-bar 36 and the main body portions 65 of the panels 15, 16 and 17. The verti-

cal front edge of the strip 37 terminates flush with the outer edge of the corresponding flange of the Z-bar 36 thereby providing a forwardly projecting flange 38 on the door of two-ply thickness. The flange 38 is adapted to engage behind the outer arm of a vertically disposed Z-bar 39 applied to the outer wall of the car adjacent the front end of the door opening. The Z-bar 38 also acts as a stop member to limit the sliding movement of the door when the same is pushed to closed position. The Z-bar 39 is preferably secured to the wall of the car by rivets extending through the same and through a wear facing strip 40 applied to the post 13 at the front end 75 of the door opening.

A Z-bar 41, having the flanges 42 and 43 thereof vertically disposed and extending upwardly and downwardly respectively from the intermediate web section 44 extends longitudinally of the upper edge of the door and is secured thereto by the flange 43 which is riveted to the front surface of the section of the flange 18 at the upper edge of the panel 15. As clearly shown in Figure 3, the flange 43 section 18 at the upper edge of the panel 15 is offset inwardly with reference to the remainder of the flange 18 thereof, a distance corresponding substantially to the thickness of the flange 43 of the Z-bar. A reinforcing 90 bridging strip 44', having the upper edge thereof bent at an angle and riveted to the flange 42 of the Z-bar 41, spans the space between the Z-bar and the main body portion of the panel 15, the lower edge of the strip being 100 riveted to the panel as clearly shown in Figure 3.

Guide brackets, in the form of Z-shaped plates are provided at the upper edge of the door, there being preferably two such plates, 105 one at each end of the door. Each plate 45 has one of its flanges secured to the flange 43 of the Z-bar 41 and the other flange thereof projecting upwardly in a plane parallel to the flange 42 of the Z-bar, thereby providing a 110 guideway therebetween adapted to accommodate a depending flange 46 of a Z-bar 47 forming the upper guide for the door, the Z-bar 47 having the remaining flange thereof secured to the lintel 14 in any suitable manner. 115

The door A is supported for sliding movement by a pair of rollers 48 disposed at the front and rear ends thereof and coacting with the angle track rail 28. The rollers are disposed within the tubular pocket defined 120 by the strip 27, Z-bar 23, flange 18 and the wall 19 at the lower edge of the panel 16, and each is mounted within a bracket 49 on a short shaft 50 extending through the side walls of the bracket, the arm 24 of the Z-bar 125 23 and a relatively large opening in the plate 27. As clearly shown in Figure 3, the Z-bar 23 is provided with a pair of suitable openings at the opposite ends thereof through which the lower sides of the rollers project. 130

It will be evident that the rollers are housed entirely within the door structure, and are therefore effectively protected from the weather.

5 The door A is provided with a suitable door operating mechanism comprising, broadly, a lever B pivotally mounted on a bracket C fixed to the side wall of a car and a link D pivotally mounted on a bracket E 10 fixed to the door A. The lever B is pivotally mounted at its upper end on the bracket C by means of a pin 51, and is provided with an operating hand grip 52 at its lower end. Intermediate the handle 52 and the pivot 15 51, the lever is provided with a cylindrical projection 53 adapted to engage within an opening 54 at the free end of the link D, pivotally connected at its opposite end by a pin 55 to the bracket E. As clearly 20 shown in Figure 2, the bracket E is of such a form as to closely fit the dished portion of the panel 16 of the door and is secured to the same by rivets extending through the main body portion of the panel. The supporting bracket C is of angle shape, has the arm thereof to which the lever is pivoted, spaced from the outer face of the Z-bar 39 25 and the other arm thereof riveted to the intermediate section of the Z-bar 39.

30 To open the door, the lever B is first swung from the full line position to the dotted line position shown in Figure 1 and the link D engaged with the projection 53. Upon movement of the lever in a counter-clockwise direction, the door will be forced open. In closing the door, the operation is the reverse of that just described, the link being engaged with the lever B when in full line position and the door being pulled shut as the lever is 35 swung to the dotted line position. Means of well known construction comprising a hasp and staple designated at 56 may also be provided for locking and sealing the door when in closed position.

40 From the preceding description taken in connection with the drawings, it will be observed that I have provided an exceedingly strong and rigid all metal door construction effectively braced against bending or distortion in all directions, as all joints thereof as 45 well as the front, rear, top and bottom edges, are braced by reinforcing strips. Furthermore, while the door embodies corrugations, the inner surface of the door is substantially 50 flat and continuous, thereby minimizing any interference with movements of the door, due to any of the lading bearing thereagainst.

55 With the construction described, it will be observed that I have provided what may be termed a tubular edge construction of the door throughout as well as tubular braces extending longitudinally of the door at the joints of adjacent panels. This construction is especially adapted to resist bending thrusts 60 exerted transversely inwardly and outward-

ly of the door and to resist bending thrusts imparted parallel to the side wall of the car in vertical and horizontal directions.

It will also be evident that the arrangement of reinforcing means as hereinbefore 70 described is especially effective in bracing sheet metal doors composed of a plurality of panels having the over-lapping portions of two adjacent panels forming the joint therebetween in the form of a corrugation, in that 75 the corrugation is not only stiffened by a reinforcing strip corresponding in shape to the corrugation, but is also spanned at the base of the corrugation by an additional reinforcing strip.

80 Referring next to the construction illustrated in Figures 6 to 9 inclusive, 111 indicates the floor boards of a box car, 112 the car side sill, 113 the door post and one end of the door opening, 114 the door lintel, and 85 A' the sliding side door.

85 The door A' is of the so-called "bottom-hung" type with the supporting rollers 115 riding upon a track 116 of angular cross section, supported by suitable brackets 117 secured to the side sill 112. The door A' herein shown is of sheet metal construction throughout, provided with a plurality of corrugations extending horizontally and is reinforced along all its edges by suitable flat 90 bracing strips 118.

95 To properly support each of the supporting rollers 115 on the door, I employ a housing 119 open at the bottom and provided with a depending flange 120 overhanging the outer 100 side of the track. The housing is provided with a suitable flange 121 at the inner side thereof by which it is fixed to the door, the same being preferably secured by rivets. A short shaft 122, having its opposite ends supported in the outer and rear walls of the housing, serves to rotatably mount the roller. The opening in the outer wall of the housing, which receives the corresponding end of the shaft, is smaller than the opening in the rear 105 wall and the shaft is correspondingly reduced at its outer end whereby the same is retained in assembled relation with the housing by its inner end abutting the outer surface of the door.

110 115 The top edge of the door is guided below a longitudinally extending bar 123 having a horizontal section 124 extending over the door and a depending outer flange 125 overhanging the upper edge of the door at the outer side thereof. The bar 123 is extended upwardly from the section 124 and has the upper edge bent at right angles and secured to the under-side of the horizontally disposed arm 126 of the door lintel 114. The lower edge 120 125 of the door engages behind the track 116 so as to prevent the bottom edge of the door from being sprung outwardly. To properly guide the upper edge of the door A', I provide the same with a plurality of guide brackets 127, 130

preferably two, one at each end of the door. One of the guide brackets is shown in detail in Figures 7, 8 and 9. Each guide bracket is preferably in the form of a casting, having 5 spaced, vertically disposed, front and back walls 128 and 129 and a horizontal bottom wall 130. The back wall 129 is provided with reduced extensions at the opposite ends thereof, forming ears 131 by which the bracket is secured 10 to the door, each ear being perforated to receive a securing rivet. The front and bottom walls of the bracket 127 are preferably reinforced by transverse ribs 133. At the upper edge, the front wall 128 is provided 15 with an inwardly projecting, horizontally disposed, longitudinal flange 134, and each extension of the back wall 129 has a guide lug 135 projecting therefrom toward the flange. As clearly shown in Figures 7 and 8, the guide 20 lugs are disposed inwardly of the rivet receiving openings and in spaced relation to the opposite ends of the bottom and front walls of the bracket, and each is notched adjacent the corresponding rivet receiving opening to provide 25 clearance for the riveting tool. The walls 128 and 129 of each bracket are adapted to accommodate the depending flange 125 of the bar 123 therebetween, and the flange 134 and the lugs 135 are adapted to coact respectively 30 with the front and rear faces of the depending flange 125 to properly guide the door during its longitudinal movement and prevent the latter from being sprung either outwardly or inwardly.

35 I have herein shown and described what I now consider the preferred manner of carrying out my invention but the same is merely illustrative and I contemplate all changes and modifications that come within the scope of 40 the claims appended hereto.

I claim:

1. In a door, the combination with a plurality of sheet metal plates, having their adjacent edges over-lapping and joined together, the over-lapping edges at each joint between the sheets being offset outwardly from the main body portion of the sheets; of a strip reinforcing each of said offset joint portions and corresponding in section thereto; 45 and a second reinforcing strip spanning each offset joint and rigidly secured to the body portions of the corresponding plates.

2. As an article of manufacture, a door comprised of sheet metal provided with bracing indentations, each of said indentations being reinforced by a correspondingly formed strip fitting within the indentation, and a second strip spanning the indentation.

3. As an article of manufacture, a door 50 comprised of a plurality of sheet metal panels having their adjacent edges over-lapping and joined together, each of said joined over-lapping portions being offset with reference to the plane of the main body portions of 55 said panels, thereby defining a corrugation,

said corrugation being reinforced by a correspondingly shaped strip fitting the inner walls of the corrugation, and by a second strip spanning the base of the corrugation and having its opposite edges secured to the 70 main body portions of two adjacent panels.

4. In a car, the combination with a sliding door of the bottom hung type; of a member fixed to the car adjacent the upper edge of the door and having a depending flange overhanging the upper edge of the door; a guide bracket fixed to the upper edge of the door, said bracket having integral means thereon engaging the front and rear surfaces of said depending flange to guide the door for sliding movement.

5. In a car, the combination with a sliding door of bottom hung type; of a member fixed to the car adjacent the upper edge of the door and having a depending flange overhanging 85 the upper edge of the door; of a guide bracket fixed to the door, said bracket having front and rear walls adapted to receive said depending flange therebetween, said walls being provided with projections adapted to coact 90 respectively with the front and rear faces of said depending flange.

6. In a car, the combination with a sliding door of the bottom hung type, of a bracket mounted on said car and arranged to carry a 95 guide, said door being provided with a flange portion disposed at one side of said guide; and means on said door having a flange co-operating with the opposite side of said guide.

7. As an article of manufacture, a guide bracket adapted to be secured to a door, said bracket including a housing open at the opposite ends and top and adapted to accommodate a guide member, one wall of said 105 housing being provided with a flange adapted to engage one side of said guide member and another wall of said housing being provided with a projection adapted to engage the opposite side of said guide member.

8. In a car door, the combination with a main body portion having an integral off-set flange extending along the rear edge thereof; of an angular section arranged along the rear edge of said door and secured to said off-set 115 flange, said angular section including a portion disposed substantially normal to the main plane of the main body portion, and including a portion projecting beyond the inner surface of said door and toward the forward 120 edge thereof in parallel relation with reference to the inner surface of said door.

9. In a car door, the combination with a main body portion having an integral off-set flange at the rear edge thereof; of an angular 125 section arranged along the rear edge of said door and secured to said off-set, said angular section including a portion extending substantially normal to the main plane of the body portion and a portion disposed beyond 130

the inner surface of said door and projecting toward the forward edge thereof in spaced relation with reference to the inner surface of said door; and a vertically extending reinforcing strip secured to said main body portion inwardly of said flanged portion and extending in spaced relation with reference to the off-set flange to said normal portion and being secured to the latter at points spaced from the forwardly projecting portion of said angular section.

10. In a car door, the combination with a main body portion made up of sheet metal and including an integral portion at the rear edge 15 of the door, extending at an angle to one side of said main plane and terminating in an integral off-set portion disposed substantially parallel with said main plane; of a reinforcing section in the form of an angular 20 bar provided with a web extending substantially at right angles to the main plane of the door, said bar being provided with a flange lying flatwise against said offset por-

tion, the web of said bar extending inwardly of the main plane of the door and terminating 25 in a portion adapted to form a spark seal; and a vertically extending reinforcing strip secured to said main body portion in its main plane, inwardly of said integral off-set portion and extending to and being secured to 30 said web in spaced relation with reference to said off-set portion.

11. A steel door comprising flanged structural steel members of relatively sturdy construction, connected together to form a substantially rectangular frame, sheet steel members of relatively light weight for covering said frame, said sheet steel members including box-like braces and panels, said sheet steel members being overlapped from top to 35 bottom of said door in positions to shed rain or other forms of precipitation.

In witness that I claim the foregoing I have hereunto subscribed my name this 5th day of June, 1924.

ALLAN S. BARROWS.
